UNITED STATES PATENT OFFICE.

FRANK V. BURTON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ADVERTISING-DISPLAY.

1,172,107.

Specification of Letters Patent. Patented Feb. 15, 1916.

Application filed November 5, 1914. Serial No. 870,476.

To all whom it may concern:

Be it known that I, FRANK V. BURTON, a citizen of the United States of America, and residing at Bridgeport, in the county of 5 Fairfield and State of Connecticut, have invented a certain new and useful Advertising-Display, of which the following is a specification.

My invention relates to an advertising 10 display and especially to an improved display for series of fittings having interchangeable parts.

In the accompanying drawings, Figure 15 1 is a broken elevation of a chart in which my improved display is illustratively embodied; and Fig. 2 shows the reverse of said chart showing the application of the display system to a plurality of series of fittings with interchangeable parts.

20 The display forming the subject of my prior Patent 1,075,009 comprises a base A on which is rotatably mounted a disk B as in Fig. 1 of the present display. The two-part devices there shown, as now, are electrical fittings each comprising a cap or base part x^1 , x^2 , x^3 , etc., and a coöperating shell part y^1 , y^2 , y^3 , etc. As in my prior display, the corresponding x parts of the several fittings are radially arranged in a circle on the 25 base or placard A just outside the periphery of the disk B, while the y parts are radially arranged at the periphery of the disk, so that upon the rotation of the disk each y part is brought consecutively into register 30 with each x part of the series of fittings.

35 As heretofore also, the disk B of Fig. 1 is provided with spirally arranged apertures C one for each shell part y and radially aligned therewith to disclose what appears beneath each aperture in the several columns 40 D printed on the base A in radial alinement with the several cap or base parts x illustrated thereon. In the display shown in my patent above mentioned, these columns 45 D consist of catalogue numbers, by which each particular combination of parts is identified. Where fittings in the series are numerous, however, the number of combinations is so multiplied that they become 50 a burden to list and a source of confusion in orders. I now propose to provide identification symbols of a different character for the different elements of the two-part device, display these symbols in different 55 manner than heretofore and incidentally, in

the form shown in Fig. 1, employ the columns D for the display of price, number of fittings in a standard package or other matter which may be deemed useful. Thus for the caps or bases x , I have provided a 60 symbol 10 of one character, viz., letters, and for the coöperating shells y , a symbol 11 of different character, viz., numerals. These symbols may be of any suitable nature; but letters and numerals are 65 convenient and moreover they lend themselves admirably to a systematized display where there is a plurality of series of two-part fittings to be displayed, as will be more fully explained with relation to Fig. 2. 70

While for a small number of fittings in a single series, it would perhaps suffice to use a single letter to identify the cap element and a single numeral to identify the shell element, I prefer to employ two letters 75 and two numerals to identify the respective parts. Thus for the series of caps the first element of the letter combination symbol may be A or B and the second letter will be any one arbitrarily chosen from the 80 alphabet to give an individual combination therewith for each separate cap construction. Similarly for the series of shell elements each number combination will begin for example with the numeral 1 or 2, and the second numeral of the symbol will be 85 arbitrarily chosen to establish an individual combination therewith peculiar to each separate shell construction. Thus for the caps the letter combination symbols may run 90 A A, or A B, D D, etc., while for the shells the numeral combination symbols may run 95 11, 18, 23, etc., and in any case the symbol for a complete fitting will comprise the separate symbols for any of the coöperating cap and shells, as A-B 13 or 13 A B, it being immaterial which symbol is placed first in order since they are different and no confusion can arise from the fact that they are combined in one order or the other. This 100 is a marked advantage over displays in which the symbols are of the same character since confusion of sequence is more likely to result in erroneous identifications of the combinations of elements which it is desired to order. 105

The adoption of independent symbols for each interchangeable part of the series of fittings permits me to display the same in juxtaposition to each part. Thus the sym- 110

bol for each cap element is arranged on the base adjacent the part it identifies, while the symbol for each shell element appears upon the rotary disk adjacent each shell represented thereon. Inasmuch as these symbols are readily observable there is no necessity for their display in joint form at the apertures C in the disk. The columns D therefore may be now used for the display of such useful information as the price of the complete fitting, and the number of fittings in a standard package. The display may be further employed to show the price of each element of the fitting when sold separately, this price being arranged on the base or disk, say at 12, adjacent the representation of each particular element. It is not always the case that the price of the complete fitting equals the sum of the prices of the two elements when the latter are sold separately.

While the display system above described is a great improvement over that heretofore employed for a series of fittings of the type referred to, it is of particular value where the manufacturer makes a plurality of series of devices of the type in question, each series having fittings which comprise certain features in common. Thus among electrical fittings, there may be (a) a series of standard size, (b) a substantially corresponding series of miniature size, and (c) a third series differing from the first for example in that the casings are of porcelain instead of metal. Thus the fittings shown in Fig. 1 may be regarded as of standard size, while in Fig. 2 the chart in the upper portion of the figure shows miniature fittings of the series (b) and the lower chart the porcelain fittings of the series (c). This display of Fig. 2 obviously presents the fittings in substantially the same manner as in Fig. 1, although possibly not with equal convenience. By arranging the caps in a horizontal line and the shells in a vertical line at one end, the squares 13 formed by the intersection of vertical and horizontal columns which correspond to the several parts, afford means for the display of the price, number of fittings in a standard package etc., such as are given in the radial columns D on the base A and viewed through the apertures C in the disk in Fig. 1. Thus the price and standard package of miniature pull sockets having a cap provided with $\frac{1}{8}$ " nipple will be found in the square formed by the intersection of the horizontal column alined with the socket shell and the vertical column alined with the specific cap in question.

If now the first letter of the cap symbol be A or B for caps in the (a) series, the first letter of the cap symbol in the (b) series may be arbitrarily chosen to differentiate this series as a whole from the (a) series, as by employing W for the initial letter of

the combination, while the first letter of the symbol for the (c) series may be again different—as P or R. At the same time the second letter of the cap combination symbol may be kept the same for corresponding parts in each series. The change in the first element of the symbol is sufficient to differentiate the series, while the second element of the symbol identifies with precision the precise member in each series, the same letter serving for corresponding elements in each series. The simplification of identification is obvious. Thus A A identifies for example a standard size metal cap with $\frac{1}{8}$ " screw nipple; W A indicates an identical cap except that it is in (b) series and of miniature size; while P A indicates a fitting of the same type but with porcelain casing.

Obviously the same arrangement of identification symbols may be employed for the coöperating shell parts in each series, using numerals instead of letters. Thus for each series, the first numeral of the combination symbol may be arbitrarily chosen to identify the series and the second numeral in the combination to identify the particular shell in the series. Thus in series (a) the first numeral for each symbol may for example be 1 or 2; in series (b) the first numeral may be 8 or 9, while in series (c) the first numeral may be 7. It will be understood of course that the numbers mentioned are arbitrarily chosen for the sake of illustration and may be any other numeral desired. The second numeral of such series serves to identify the particular shell in each series and like numerals are employed to identify corresponding shells in each series. Thus the combination 15 will identify the metallic shell element of a standard size pull socket; 85 the same in diminutive form and 75 the corresponding part of a porcelain pull socket.

The identification symbol for a complete device will of course comprise the combination of the symbols for the respective cap and shell parts. Thus a pull socket of standard size with metallic casing and $\frac{1}{4}$ " screw nipple will be represented by the symbol A A 15; while the same in diminutive size would be indentified by the symbol W A 85 and in porcelain by P. A 75. The value of a display having identification symbols thus correlated for a plurality of series of fittings having certain general features in common will readily commend itself to the manufacturer as well as to the purchasing contractors, jobbers, etc., since obviously the retention in the memory of a long series of perfectly arbitrary catalogue numbers is no longer necessary. Moreover by displaying the cap and shell parts independently and giving to each its own individual identification symbol, the parts may be readily specified for orders, without the lengthy

descriptions heretofore required in such cases.

While in the present illustration the fittings of series (b) and (c) are shown in charts on the back of the placard A, it is obvious that the shell elements might be displayed at the periphery of a disk and the cap elements on a placard around the disk, as in Fig. 1. In like manner the fittings of series (a) may be arranged in chart form as in Fig. 2 if desired. Even other methods of display may be employed, if preferred. That shown in the drawings is preferred by me however as the most compact, efficient and convenient. In any event, however, it affords a great saving of cataloguing space, a great convenience to the buyer, since it minimizes the number of arbitrary symbols necessary to remember to identify the several fittings if the display is not available to order from, and it saves the shipper from erroneous shipments since confusion of symbols is practically impossible.

I claim as my invention:—

1. An advertising display comprising separate representations of each part of a series of two-part devices each corresponding part in the series being adapted to combine with any of the coöperating parts in the series to form a complete device, an independent identification symbol for each of the coöperating parts throughout the series, a combination of said symbols serving to identify a complete fitting of particular type.

2. An advertising display comprising separate representations of each part of a series of two-part devices each corresponding part in the series being adapted to combine with any of the coöperating parts in the series to form a complete device, independent identification symbols of one character for corresponding parts of each device in the series, and independent identification symbols of different character for each of the coöperating parts of said series, a combination of two symbols of different character serving to identify a complete device of particular type.

3. An advertising display comprising separate representations of each part of a series of two-part devices each corresponding part in the series being adapted to combine with any of the coöperating parts in the series to form a complete device, independent letter symbols for corresponding parts of each device in the series, and independent number symbols for each of the coöperating parts of said series, the combination of a letter and a number symbol serving to identify a complete device of particular type.

4. An advertising display comprising separate representations of each part of a series of two-part devices each correspond-

ing part in the series being adapted to combine with any of the coöperating parts in the series to form a complete device, independent letter symbols for corresponding parts of each device in the series, said letter symbol comprising a plurality of letters, and independent number symbols for each of the coöperating parts of said series, each number symbol comprising a plurality of numerals, the combination of a letter and a number symbol serving to identify a complete device of particular type. 75

5. An advertising display, comprising separate representations of each part of a plurality of series of two-part fittings each corresponding part in each series being adapted to combine with any of the coöperating parts in that series to form a complete device, independent letter symbols for corresponding parts of each device in each series, each letter symbol comprising a plurality of letters, portion of said letter symbol serving to identify a particular series and differing in each series, and another portion of said letter symbol serving 90 to identify a particular part in a series and corresponding for corresponding parts in each series, together with independent number symbols for each of the coöperating parts of each of said series, each of said number symbols comprising a plurality of numerals, portion of which identify a particular series and differing for each series, and another portion of said symbol serving 95 to identify a particular part in a series and 100 corresponding for corresponding parts in each series; the combination of a letter symbol and a numeral symbol serving to identify a particular device.

6. An advertising display comprising 105 separate representations of each part of a series of two-part devices each corresponding part in the series being adapted to combine with any of the coöperating parts in the series to form a complete device, an independent identification symbol for each of the coöperating parts throughout the series, a combination of said symbols serving to identify a complete fitting of particular type, together with a column alined with 110 each corresponding part of the series and displaying the price of a complete device when said part is combined with any of the coöperating parts of the series.

7. An advertising display comprising 120 separate representations of each part of a series of two-part devices each corresponding part in the series being adapted to combine with any of the coöperating parts in the series to form a complete device, and 125 for each part of each fitting an independent identification symbol, a combination of said symbols serving to identify a complete fitting of particular type, together with a column alined with each corresponding part 130

- of the series and displaying the number of complete devices comprised in a standard package when said part is combined with any of the coöperating parts of the series.
- 5 8. An advertising display comprising separate representations of each part of a series of two-part devices, said series comprising a plurality of different corresponding parts and at least one coöperating part
- 10 with which any of said corresponding parts may be combined to form a complete fitting, an independent identification symbol for each of the parts throughout the series, a combination of said symbols serving to
- 15 identify a complete fitting of particular

type, together with an information chart on said display conveying independent information in regard to each possible combination of said parts and means for readily associating with the representations of the 20 parts, the information on said chart with reference to any particular combination of said parts.

In testimony whereof I have signed my name to this specification, in the presence 25 of two subscribing witnesses.

FRANK V. BURTON.
